UNITED STATES PATENT OFFICE.

WILLIAM LEE, OF PAWTUCKET, RHODE ISLAND.

CARDING.

1,100,082.

Specification of Letters Patent. Patented June 16, 1914.

Application filed October 9, 1912. Serial No. 724,714.

To all whom it may concern:

Be it known that I, WILLIAM LEE, citizen of the United States, and resident of Pawtucket, in the county of Providence and State of Rhode Island, have invented new and useful Improvements in Carding, of which the following is a specification.

My invention relates to the art of carding textile fibers, and consists of a method auxiliary to the carding operation by which a cotton-carding machine is enabled to run without interruption at sustained efficiency, until such time as it becomes necessary to re-grind the teeth of the card cylinder. This method renders it unnecessary to strip and clean the card-cylinder every two or three hours, as mill practice heretofore has required; and is characterized by continuous packing of the uncarded or residual fiber left on the cylinder into a close felt at the bases of the card-teeth, so that the tips of the teeth are kept free from those fibers which form neps when the carding machine is operated as heretofore. The dirt which is not taken care of by the top flats is also packed into the felted mass at the bases of the card teeth. Since the teeth on a card cylinder are ranged very close together a mechanical fiber packing device is hardly feasible; I employ a pneumatic packing device for this purpose, directing a forcible jet of air against the cylinder at such angle as to render its fiber packing operation effective. The performance of this method is a special application of and involves, broadly speaking a method of felting fibers for general purposes.

My method may be carried into effect by means of apparatus such as is shown in the accompanying drawings in which—

Figure 1 is a diagrammatic representation of a carding machine; Fig. 2 is a view partly in cross section of the pneumatic fiber packer and its carrier; and Fig. 3 is an end elevation of the lower part of the carding machine, showing the pneumatic fiber-packer; and its carrier.

Referring to Fig. 1:—C represents the main cylinder of a cotton carding machine, which during the carding operation rotates in the direction shown by the arrow *a*, taking cotton fiber from the licker-in *L*, subjecting it to the action of the top flats at *F*, and delivering the carded fiber to the doffer cylinder *D*. In the normal operation of a carding machine as heretofore universally

known and practised, part of the fiber is truly and effectively carded and transferred to the doffer cylinder, to be removed therefrom in the form of a web, part is taken off by the top flats, together with dirt, and the residual part remains in the teeth of the card cylinder, when, after a period of accumulation, it interferes with the effectiveness of the carding operation by forming neps. The detrimental effect of this accumulated residual fiber has heretofore made it necessary to stop a carding machine every two or three hours and strip it clear of the accumulated residual fiber, together with such dirt as has become entangled in it. The characteristic feature of my method is in treatment of this portion of the cotton fiber which I have termed the residual fiber, since it is that portion left over after the operations of the cylinder and top flats have disposed of the other parts of the fiber. As the residual fiber is passing from the doffer *D* to the licker-in *L*, I cause it to be compacted and pressed against the cylinder so as to be removed from the region near the tips of the card teeth and lodged at and near the bases thereof. The means by which I find this packing to be well accomplished consists in an air jet, which, by forcibly impinging against the cylinder carries the residual fibers (and such dirt as may be present) inward to the bases of the teeth and there forms of said fiber a closely matted felt. An air nozzle *N*, communicating with a flexible pipe *P*, is so controlled as to traverse across the cylinder in a line parallel to the axis thereof.

The details of the air jet attachment are shown in Figs. 2 and 3. In these figures *O* represents the card cylinder rotating in the direction of the arrow *a*. *S* is a screw provided with right and left handed traversing threads, and *H* a housing for the screw *S*, slotted longitudinally at *H'*. *A* is a collar loosely surrounding the screw *S*, *B* a follower, swivel-mounted by its stem *B'*, in the collar *A*, which extends through the slot *H'* to form the hanger *D'*, to which the nozzle *N* is attached, with which the flexible pipe *P* communicates; said pipe being connected with a source of air pressure (not shown). *E*, *E'* are standards on which the screw *S* is journaled, and *P'* a pulley by means of which the screw *S* may be rotated. As the screw *S* rotates continuously in one direction, the follower *B* traverses back and

forth in the right and left-handed traversing threads, carrying collar A, hanger D' and the nozzle N with it. The angle of incidence of the air jet from the nozzle N upon the cylinder C should be such as to crowd the residual fibers into the card teeth. This direction is indicated by the arrow b, and may be varied within reasonable limits. Under normal conditions, with a nozzle ori-

10 fice $\frac{1}{16}$ inch in diameter within $\frac{1}{4}$ inch of the tops of the card teeth, and an air pressure of five or six pounds per square inch, and a rate of traverse of the nozzle across the card cylinder from five to ten times a

15 minute, the residual fibers will be compacted at the base of the card teeth, leaving the tops thereof clean and in proper condition for good carding, which, with this method in operation, continues without interruption or decline of efficiency, until the wearing of the card teeth themselves makes it necessary to stop the machine, strip the cylinder, and

20 regrind the teeth.

By stripping the accumulated felt formed by the residual fibers under the method above described, in such manner as not to break it except at one line of division, a sheet of elastic cotton felt or wadding is obtained, which has many uses and is de-

25 cidedly valuable as a by-product.

What I claim and desire to secure by Letters Patent is:

1. The method of maintaining the card teeth of a carding machine cylinder in effective operative condition, which consists in

30 directing the air jet on the residual fibers among the card teeth during transit of said

fibers from the doffer cylinder to the licker-in to crowd said fibers to the bases of the teeth.

2. The method of maintaining the card teeth of a carding machine cylinder in effective operative condition, which consists in directing a transversely reciprocating air jet on the residual fibers among the card teeth during transit of said fibers from the doffer cylinder to the licker-in to crowd said fibers to the bases of the teeth.

3. In a carding machine, the combination with the carding cylinder, of pneumatic means to exert pressure on the residual fibers, after doffing, among the card teeth of said cylinder, to crowd said fibers to the bases of the teeth.

4. In a carding machine, the combination with the carding cylinder, of transversely reciprocating means to exert pressure on the residual fibers, after doffing, among the card teeth of said cylinder, to crowd said fibers to the bases of the card teeth.

5. In a carding machine, the combination with the carding cylinder, of transversely reciprocating pneumatic means to exert pressure on the residual fibers, after doffing, among the card teeth of said cylinder, to crowd said fibers to the bases of the card teeth.

Signed by me at Boston, Massachusetts, this twenty first day of September, 1912.

WILLIAM LEE.
